UNITED STATES PATENT OFFICE.

JOHN W. TIDWELL, OF TULSA, OKLAHOMA, ASSIGNOR OF ONE-HALF TO JAMES FITZ
GERALD, OF TULSA, OKLAHOMA.

REVOLVING VENTILATOR.

1,407,179.

Specification of Letters Patent. Patented Feb. 21, 1922.

Application filed June 26, 1919. Serial No. 306,802.

To all whom it may concern:

Be it known that I, JOHN W. TIDWELL, a citizen of the United States, residing at Tulsa, in the county of Tulsa and State of Oklahoma, have invented certain new and useful Improvements in Revolving Ventilators; and I do declare the following to be a full, clear, and exact description of the invention, such as will enable others skilled in the art to which it appertains to make and use the same.

My invention relates to improvements in ventilators of the type in which the foul air is exhausted through a revolving cowl which is turned by the wind, to effectively equalize the force of the latter to induce the exhaust currents through the device.

One object of the invention is to provide a ventilator of the class described having a novel form of self-lubricating bearing upon which the cowl revolves.

Another object is to provide a pair of damper plates for closing the ventilator when required, and unique means for mounting said damper plates.

Yet another object is to utilize part of the bearing supporting means as means for supporting the damper plates.

A still further object is to provide a ventilator which may be easily and inexpensively manufactured, yet one which will be highly efficient and durable.

With the foregoing in view, the invention resides in the novel construction and arrangement of parts hereinafter fully described and claimed, the descriptive matter being supplemented by the accompanying drawings which form a part of this application.

Figure 1 is a side elevation of a ventilator constructed in accordance with my invention.

Fig. 2 is a vertical section of the ventilator.

Fig. 3 is a vertical section on the plane indicated by the line 3—3 of Fig. 2.

Fig. 4 is a view similar to Fig. 2, but showing the damper plates in open position.

Fig. 5 is a detail horizontal section as indicated by the line 5—5 of Fig. 2.

Fig. 6 is a perspective view of the exhaust passage and the socket member of the bearing mounted therein.

Fig. 7 is an enlarged vertical section of the bearing.

Fig. 8 is a perspective view of one of the damper plates.

In the drawings above briefly described, the numeral 1 designates an exhaust passage for the foul air or the like from the building, said passage being connected in any preferred manner with the roof or other suitable part. In the present showing, the passage 1 is provided with a flared apron 2 having V-shaped notches 3 in its lower edge to straddle the arch of the roof or other part upon which the ventilator is mounted. A suitably shaped cowl 4 is disposed at the upper end of the passage 1 and is mounted in a novel manner to be described. This cowl is provided with the usual vane 5 for turning it by the action of the wind, and the outlet end 6 of said cowl is preferably provided with a ring 7 spaced around said end and carried thereby through the instrumentality of suitable brackets or the like 8. The ring 7 is in the form of a frustum of a hollow cone and it serves to so direct the wind currents as to most effectively create suction through the ventilator to exhaust the foul air, gases, etc. I preferably provide the cowl 4 with a weight 9 disposed opposite the vane 5, to balance the cowl, thus insuring proper turning thereof. This weight also serves more or less as a drag to prevent lashing of the cowl to and fro.

The top of the cowl 4 is provided with an opening 10 and the upper end of a tubular shaft 11 extends through said opening, being provided with a shoulder such as a nut 12, upon which the cowl top rests and is held by a screw cap 13 which is threaded on the upper end of the shaft 11, above the cowl. The shaft 11 forms an oil reservoir and may be filled by removing the cap 13. The lower end of the shaft is closed by a screw cap 14 and said shaft is provided with one or more oil discharge openings 15. For bracing the shaft 11 with respect to the cowl 4, a channel bar or other suitable means 16 is employed.

The lower portion of the shaft 11 is loosely received in a tubular socket member 17 which is fixedly mounted within the passage 1, said socket member being preferably formed of a single piece of piping closed at its lower end by a screw cap 18 while its upper end is provided with a reducer 19 which prevents the entrance of foreign matter. Oil is supplied to the socket member 17 from the tubular shaft 11 and in the pres-

ent showing, the oil enters said socket member through the openings 15 in the shaft. A ball bearing 20 is preferably interposed between the two caps 14 and 18 to anti-frictionally support the shaft 11, and two or more floating rings 21 loosely surround the shaft within the upper and lower ends of the socket member 17. The upper ring 21 is mounted loosely between circumferential ribs 22 on the shaft, while the lower ring 21 may be held against upward movement by a rib 23 and against downward movement by the cap 14. These floating rings retain the shaft 11 properly centered in the bearing member 17 and it will of course be understood that they could be mounted in any suitable manner. Since the socket member is filled with oil from the shaft 11, the latter and the cowl will revolve with practically no resistance and the device will thereby be extremely sensitive.

For mounting the socket member 17, I provide bar means extending across the passage 1, said bar means being shown as consisting of upper and lower channel bars 24 and 25, the flanges 26 of the latter being directed upwardly for a purpose to appear. The socket member 17 passes through and is secured in openings formed in the bars 24 and 25 and is rigidly held in vertical position by said bars. In the present showing, I have utilized the flanges 26 for supporting a pair of damper plates 27, said plates being disposed in the passage 1 with their inner edges resting on said flanges 26. The plates 27 are provided with vertical shoulders 28 engaging the outer sides of the flanges 26, said shoulders 28 and the inner edge portions of the damper plates 27 forming right angular seats which pivotally mount the plates on the bar 25. It will of course be understood that these seats may vary and that the bar means supporting them need not necessarily be formed by one bar such as 25.

Although any adequate means could be provided for operating the damper plates 27, each of said plates is preferably provided with an arm 29 secured to its lower side and extending beyond its pivotal axis, the free ends of the two arms being con-

nected to a suitable operating wire, chain or the like 30. Normally, the weight of the plates 27 and their arms 29, holds said plates in closed position, but when the wire 55 or the like 30 is pulled downwardly, said plates will be opened as shown in Fig 4.

The device is intended principally for ventilating buildings in which gasoline is manufactured or used, but it may of course 60 be employed in connection with numerous other buildings, and regardless of its use, the device will be highly efficient and reliable for exhausting the foul air and gases, easy operation being insured at all 65 times by the self-lubricating bearing. Whenever required, the ventilator may be closed by the plates 27. In addition to these advantages, the entire device may be easily and inexpensively manufactured and marketed at small cost.

Since probably the best results are obtained from the details disclosed, they may well be followed, but within the scope of the invention as claimed, numerous minor 75 changes may well be made.

I claim:

1. In a ventilator, an exhaust passage, a cowl at the upper end of said passage, a tubular shaft depending from said cowl and forming an oil reservoir, a fixed tubular socket member in which said shaft is received and into which it discharges oil, a ball in said socket on which said shaft rests, spaced circumferential shoulders on said shaft, and 85 floating rings surrounding said shaft between said shoulders.

2. In a cowl bearing, the combination with a fixed vertical socket and a thrust bearing within its lower end, of a cowl supporting shaft extending into said socket, a ring loosely surrounding said shaft and in running contact with the wall of the socket, a shoulder on said shaft contacting with the upper side of said ring, and a cap 95 threaded on the lower end of said shaft, said cap serving to retain said ring against said shoulder and acting also as a thrust surface resting on said thrust bearing.

In testimony whereof I have hereunto 100 set my hand.

JOHN W. TIDWELL.
